UNITED STATES PATENT OFFICE

128,264

DESIGN FOR A WHEEL SUPPORTING TRUCK FOR SCOOTER CARS

Joseph M. Rodriguez, Brooklyn, N. Y.

Application January 2, 1941, Serial No. 97,785

Term of patent 14 years

To all whom it may concern:

Be it known that I, Joseph M. Rodriguez, a citizen of the United States, residing at Brooklyn, in the county of Kings and State of New York, have invented a new, original, and ornamental Design for a Wheel Supporting Truck for Scooter Cars, of which the following is a specification, reference being had to the accompanying drawing, forming part thereof.

Fig. 1 is a front elevational view.

Fig. 2 is a side elevational view.

Fig. 3 is a plan view thereof.

Fig. 4 is a perspective view of a wheel supporting truck for scooter cars, showing my new design.

I claim:

The ornamental design for a wheel supporting truck for scooter cars, as shown.

JOSEPH M. RODRIGUEZ.
